UNITED STATES PATENT OFFICE.

NICHOLAS W. ANTHONY, OF NEW YORK, N. Y.

BURNER.

1,184,809.

Specification of Letters Patent. Patented May 30, 1916.

Application filed December 31, 1915. Serial No. 69,661.

To all whom it may concern:

Be it known that I, NICHOLAS W. ANTHONY, a citizen of the United States, and resident of New York, county and State of New York, have invented certain new and useful Improvements in Burners, of which the following is a specification.

This invention relates to burners and more particularly to improvements in the details 10 of construction of the type of burner illustrated and broadly claimed in my earlier application No. 48,904 filed September 3, 1915.

It is the object of the present invention to provide a burner of the type described in my 15 aforesaid earlier application which will be comparatively simple in construction and adapted to supply the requisite amounts of air on the interior and exterior of the ring of fuel spray so as to have a maximum efficiency of combustion and produce an annular flame.

Other objects will be apparent from the following description taken in connection with the accompanying drawings, in which,

25 Figure 1 is a longitudinal section through a burner embodying my improvements; Fig. 2 is an elevation of the front end of the same; and Fig. 3 is a section on the line 3—3 of Fig. 1.

30 Referring to the drawings, 10 indicates the burner casing which is supplied with air through the connection 11. The casing is preferably provided with a removable plug 12 in its rear wall in which there is arranged the fuel pipe 13 which is arranged substantially at the center of the casing and extends to a point near the front end thereof. A conical head 14 is secured to the forward end of the pipe 13 and provided with a central recess 15 and a series of recesses 16 arranged in a circle about the recess 15. Ports 17 extend from the recess 15 rearwardly through the head 14 to convey air from the interior of the casing to the recess 15 whence

45 it is discharged in the manner hereinafter described. The recesses 16 are separately connected with the interior of the fuel supply pipe 13 by ports 18 so that each of these recesses will receive a supply of fuel directly 50 from the pipe 13.

In each of the recesses 16 there is secured a nozzle or nebulizer 19, preferably adapted to break up the fuel into a fine spray which is discharged through the central opening 20. It will be understood that the spray discharged from each of the nozzles 19 is in the

form of a cone and the series of nozzles, being arranged in a circle, will produce a ring of fuel spray. Each of the nozzles 19 may be provided with recesses 21 in the front surface thereof to receive a spanner wrench for the purpose of securing the nozzles in the recesses 16.

A deflector 22 is secured to the head 14, in alinement with the recess 15 by a screw 65 threaded connection 23 so that the deflector may be adjusted to any desired position. A lock nut 24 may be provided for securing the deflector 22 in any position to which it is adjusted. The deflector 22 is preferably in 70 the form of an outwardly flaring cone which will be adapted to direct the current of air from the recess 15, substantially at right angles to and against the inner side of the ring of fuel spray from the nozzles 19. The 75 air from the recess 15, being formed into an annular current by the deflector 22 and striking the ring of fuel spray substantially at right angles, will thoroughly mingle with the particles of fuel so that all portions adjacent the inner side of the ring of spray 80 will receive the requisite amount of air to burn the fuel with the maximum efficiency.

A cap 25 is secured on the exterior of the casing 10 by the screw threads 26 and 85 is provided with an inturned conical flange 27 which coöperates with the head 14 to deflect the air current, which is discharged around the head 14, substantially at right angles to and against the outer side of the 90 ring of fuel spray. In this way the portions of the fuel adjacent the outer side of the spray will receive the requisite amount of air for the maximum efficiency of combustion and therefore the flange 27 coöperates 95 with the deflector 22 to provide on the exterior and interior of the ring of spray the necessary amount of air and to also, due to the force of the air currents, produce a perfectly formed annular flame.

100 The burner above described is particularly designed to be supplied with low pressure air and the arrangement of the nozzles 19 and the supply of air to the inner and outer sides of the ring of spray gives to the 105 burner a large heat generating capacity.

While the form of the invention illustrated in the drawings is a specific embodiment of the invention described and claimed in my aforesaid earlier application, it will be 110 understood that the improvements herein claimed may be embodied in burners differ-

ing in minor details from that illustrated and therefore it will be understood that the invention is not limited to the exact details shown and described but comprises all modifications thereof which come within the scope of the appended claims.

Having described the invention what is claimed is:

1. In a device of the class described, the combination of a casing, an air connection thereon, a fuel supply pipe in the casing, a head on said pipe spaced from the casing and provided with a plurality of ports, communicating with the interior of the pipe, and a central air opening, a series of nozzles arranged in a circle about said opening and adapted to coöperate to produce a ring of fuel spray, each nozzle being separately supplied by one of said ports, a deflector adjustably connected with said head and adapted to form the air passing through said opening into an annular current and direct the same against said ring of fuel spray, and means for directing a current from around said head against the outer side of said ring of spray.

2. In a device of the class described, the combination of a casing, an air connection thereon, a fuel supply pipe in the casing, a conical head on said pipe provided with a central recess and a series of recesses arranged in a circle about the central recess, said head having one or more ports extending to the rear thereof from said central recess for supplying air to the latter and

ports separately connecting each of the recesses of said series with said pipe, spraying nozzles secured in said series of recesses and coöperating to form a ring of fuel spray, a deflector arranged in said central recess and adapted to direct the air therefrom in the form of an annular current against the inner side of said ring of spray, and means for directing a current of air from around said head against the outer side of said ring of spray.

3. In a device of the class described, the combination of a casing, an air connection thereon, a fuel supply pipe extending centrally through the casing, a conical head on the end of said pipe provided with a central recess and one or more openings extending rearwardly from said recess, and a series of recesses arranged in a circle about the central recess, said head having ports separately connecting each of the recesses of said series with said pipe, spraying nozzles secured in said series of recesses and coöperating to form a ring of fuel spray, an adjustable deflector arranged in alinement with said central recess and adapted to direct the air therefrom in the form of an annular current against the inner side of said ring of spray, and a conical cap adjustably secured on said casing and adapted to coöperate with said head to direct the air discharged around the latter against the outer side of said ring of spray.

In testimony whereof I affix my signature.
NICHOLAS W. ANTHONY.
